UNITED STATES PATENT OFFICE.

JOHN F. JOHNSON, OF BELLEVUE, PENNSYLVANIA, ASSIGNOR TO PITTSBURGH PLATE GLASS COMPANY, A CORPORATION OF PENNSYLVANIA.

PLASTER-GUN APPARATUS.

Application filed June 10, 1925. Serial No. 36,136.

The invention relates to apparatus for applying cement or plaster of Paris to the grinding tables employed in the surfacing of plate glass, and involves a modification of the apparatus shown in my Patent No. 1,223,586. It has for its object the provision of improved apparatus of the type mentioned particularly adapted for use in the so-called straightaway grinding and polishing 10 operation in which the glass is applied to a series of cars or tables arranged so as to move continuously in a train beneath a series of grinding and polishing machines. One embodiment of the invention is illustrated in 15 the accompanying drawings wherein:

Figure 1 is a plan view of the general arrangement. Fig. 2 is a side elevation of the general arrangement. Fig. 3 is a plan view of the air piping lay out. Fig. 4 is 20 a vertical section on an enlarged scale through a portion of the apparatus. Fig. 5 is a detail section through the air control valve. And Fig. 6 is a detail view, partially in side elevation and partially in section 25 of the hydrating or mixing nozzle and the connections thereto.

Referring to the general arrangements of Figs. 1 and 2, 1, 2, 3, etc. are a series of cars or tables mounted on tracks 4 and 30 adapted to carry sheets of glass mounted thereon beneath a series of grinding and polishing machines. 5 and 6 are a pair of plaster bins mounted above the space between the tracks, and 7 and 8 are a pair of plaster 35 containers in position to receive the plaster from the bins and provided with suitable air pressure means, as later described for distributing the plaster to the hydrating nozzles 9 and 10, and 11 and 12, the nozzles 9 and 10 being adapted to supply cars or tables on 40 one track and the nozzles 11 and 12 being adapted to supply the cars or tables on the other track.

Each of the containers 7 and 8 is provided 45 upon its interior with an agitator 13 (Fig. 4) and these agitators are rotated from the motors 14 and 15 operating through the reducing mechanism in the casings 16 and 17. Water is supplied for the hydrating 50 operation from the mains 18 and 19 extending longitudinally of the tracks, and air under pressure for the nozzles is supplied from the tank 20, such tank being replenished from the pipe 21 leading to a compressor, which is not shown.

Leading from the lower end of the plaster containers 7 and 8 are the pairs of pipes 22 and 23, and 24 and 25 for conveying the plaster from the containers to the hydrating nozzles 9, 10, 11 and 12, such pipes being made of flexible material, such as rubber hose. Also leading from the water mains 18 and 19 to the hydrating nozzles are the pipes 26, 27, 28 and 29, such pipes also being made of rubber hose. For convenience in handling, the plaster hose and water hose for each nozzle are preferably secured together throughout the major portion of their length by any suitable means, and to keep them out of the way, they are 60 looped to supporting trolleys 30, 31, 32 and 33 mounted upon the trolley rails 34 and 35 extending longitudinally of the tracks. Extending longitudinally of the tracks adjacent the trolley rails 34 and 35 are a pair 65 of air lines 36 and 37 supplied from the air tank 20 through the pipe 38. The flow of air from these pipes to the containers 7 and 8 is controlled from any one of a series of valves 39, 40, 41, etc., as more fully described later, whereby the operator of the hydrating nozzle is able to operate a valve 70 at any point along the track by moving only a short distance.

The arrangement of the apparatus for supplying the cars on the two tracks is the same throughout, and this is also true with respect to the two supply nozzles on each side, such as for instance, the nozzles 9 and 10, so that only one of these nozzles and 80 its operating mechanism and connections will be described, the one selected being the nozzle 10. The nozzle 10 comprises a tube fitting into the casting 42 (Fig. 6) and suitably packed, as indicated at 43. This casting 85 42 is connected to the plaster pipe 23 and water pipe 27 by means of the fittings 44 and 45, the flow through the water pipe 27 being controlled by means of the globe valve 46, while the flow through the plaster pipe is controlled from the valves 39, 40 and 41, as later described. The nozzle tube is perforated, as indicated at 47, so that 90 when plaster is being carried under air pressure through the nozzle and water is flowing through the pipe 27, a mixture of the plaster and water occurs inside of the nozzle and such mixture is carried out and deposited 95 upon the surface of one of the grinding tables, the operator manipulating the nozzle 100 105 110

zle so as to distribute an even film of the mixture over the surface of the table preliminary to the laying of a sheet of glass.

The connections between the plaster pipe 23 and the container 7 from which it is supplied will be seen by reference to Fig. 4. This pipe is connected to the valve casting 48 which in turn is connected to the pocket 49 at the bottom of the container. This pocket is supplied with air under pressure from the pipe 50, and a flow of air into the pocket from this pipe 50 carries the plaster into the pipe 23 and through such pipe to the nozzle 10. The pocket 49 is fed with plaster from the container 7 by means of the rotating feeder 51 connected to the shaft 52 which also carries the agitator 13 heretofore referred to. This shaft is journaled in the bottom of the container and packed by means of the stuffing box 53. The shaft is driven from the shaft 54 by means of the gears 55 and 56, the shaft 54 being driven from the motor 14 through the intermediary of the gearing in the casing 16. Air under pressure is supplied to the top of the casing 7 through the pipe 57, and a closure is provided in the form of a bell 58 mounted upon the arm 59 which is in turn carried by the shaft 60.

Extending through the casing 48 is a rubber tube 61 constituting a spincter valve which may be closed by supplying air pressure through the pipe 62. Air is also continuously supplied to the plaster pipe 23 through a by-pass pipe 63 (Figs. 3 and 4), so that when the tube 61 is closed, there is a continuous flow through the plaster pipe so that it is cleaned out and danger of clogging between operations is avoided. One of the series of valves 39, 40, 41, etc. is shown in Fig. 5, such valve being arranged to control the flow of air through the pipes 50 and 23, the arrangement being such that when the flow of air to the pipe 50 is cut off, the casing 48 is supplied with air pressure closing the tube 61, and when the flow of air through the pipe 50 is again applied, the flow through the pipe 62 is cut off, and it is vented to the atmosphere so that the tube 61 is at this time open. In Fig. 5, the plug member 64 of the valve 39 is in position permitting the flow of air from the air line 36 to the pipe 50 so that there is a flow of air through the pocket 49 (Fig. 4) and the plaster tube 23 so that the nozzle 10 is supplied with plaster, the valve 46 being at the same time open so that a mixture of water and plaster flows through the nozzle to the table. At this time, the end of the pipe 62 leading from the spincter casing is brought into connection with a vent passage 65 leading to the atmosphere, so that the spincter tube 61 is free to open and permit a flow of plaster therethrough. The valve plug 64 is operated by a wheel 66 provided

with the operating ropes 67 and 68, and when it is desired to discontinue the operation of the nozzle, the rope 68 is pulled down rotating the plug 90 degrees and bringing the passage 69 through the plug so that it registers with the ends of the pipes 36 and 62. This movement cuts off the supply of air pressure to the pipe 50 and causes an application of air pressure to the interior of the casing 48, which carries the spincter tube 61, thus closing this valve and cutting off any flow of material therethrough, which might otherwise occur because of the application of pressure to the container from the pipe 57. Co-incident with the operation of the plug 64 to cut off the flow of air to the nozzle, the water valve 46 is operated to cut off the supply of water. The air connections from the series of valves 39, 40, 41 will be seen by reference to Fig. 3, the set of connections for each valve being similar to that as above described in connection with the valve 39. The application of air pressure to the container above the plaster and also to the lower portion through the pocket 49 insures a uniform feed of plaster to the nozzles. The air above the plaster compacts it and prevents the formation of voids in the bottom portion of the container so that the pocket 49 is more reliably supplied with plaster than it would be if no air pressure were applied above the plaster. The agitator 13 prevents any caking of the plaster which might interfere with the uniformity of the feed to the pocket 49.

What I claim is:

1. In combination in apparatus for applying a mixture of plaster and water to the tops of a series of grinding tables mounted for movement along a track, and having a source of water supply, a source of air pressure, a plaster container, a hydrating nozzle, and flexible plaster and water pipes leading from said container and source of water supply respectively to said nozzle; an air line extending along the track and having a connection with said source of air supply, a valve in the plaster pipe having air operated closure means, a pair of connections from said air line, the first of which leads to and operates said closure means, and the second of which leads to said container at the inlet end of the plaster pipe, and a valve arranged to control the flow of air from said air line to the pair of connections, such valve in one position permitting a flow of air through the first connection and cutting off the supply to the second one, and in its other position permitting a flow of air through the second connection and cutting off the supply to the first one.

2. In combination in apparatus for applying a mixture of plaster and water to the tops of a series of grinding tables mounted for movement along a track, and having a

source of water supply, a source of air pressure, a plaster container, a hydrating nozzle, and flexible plaster and water pipes leading from said container and source of water supply respectively to said nozzle; an air line extending along the track and having a connection with said source of air supply, a valve in the plaster pipe having air operated closure means, a plurality of pairs of connections from said air line, the first connection of each pair leading to said air operated closure means, and the second connection of each pair leading to the container at the in-

let end of the plaster pipe, and a valve for each pair of said connections, such valve 15 in one position permitting a flow of air through the first connection, and cutting off the supply to the second one, and in its other position permitting a flow of air through the second connection, and cutting 20 off the supply to the first one, said valves being arranged in series along said track.

In testimony whereof, I have hereunto subscribed my name this 2nd day of June, 1925.

JOHN F. JOHNSON.
